UNITED STATES PATENT OFFICE

157,474

FAN

Guy S. Faber, Chicago, Ill., assignor to Dearborn
Stove Company, a corporation of Illinois

Application May 11, 1949, Serial No. 2,567

Term of patent 14 years

(Cl. D26—7)

To all whom it may concern:

Be it known that I, Guy S. Faber, a citizen of the United States, residing at Chicago, in the county of Cook and State of Illinois, have invented a new, original, and ornamental Design for a Fan, of which the following is a specification reference being had to the accompanying drawing forming part thereof.

Figure 1 is a front view of a fan, showing my new design;

Figure 2 is a side elevational view; and

Figure 3 is a rear view thereof.

I claim:

The ornamental design for a fan, as shown.
GUY S. FABER.
